UNITED STATES PATENT OFFICE.

JOHN T. ELLIS AND ORA A. KERN, OF NASHVILLE, TENNESSEE.

EXPLOSIVE-ENGINE ATTACHMENT.

1,417,308.

Specification of Letters Patent. Patented May 23, 1922.

Application filed April 14, 1921. Serial No. 461,354.

To all whom it may concern:

Be it known that we, JOHN T. ELLIS and ORA A. KERN, citizens of the United States, residing at Nashville, in the county of Davidson and State of Tennessee, have invented 5 certain new and useful Improvements in an Explosive-Engine Attachment, of which the following is a specification.

The invention relates to an improvement 10 in attachments for explosive engines, and more particularly to a heating attachment for the fuel supply systems thereof.

The principal object of the invention is to 15 provide for a heating means for the fuel supply of an explosive engine, and one in the form of an attachment or accessory to such engine, whereby to effect a vaporization of the fuel just prior to its discharge into the cylinder, or cylinders of an engine; 20 for the more perfect combustion of the fuel; for a marked lessening in amount of carbon deposit within the cylinder or cylinders from such combustion therein; and for obtaining maximum power from a minimum fuel con- 25 sumption, with better engine performance and a more rapid and smooth acceleration thereto.

Another object of the invention is to pro- 30 vide for an attachment of the character men- tioned, and one in the form of an electric heating coil adapted to be removably inter- posed in the path of the fuel at a point, either within the carburetor, or the engine mani- 35 fold, or between the same as may be desired or convenient, and which may be readily connected to or disconnected from a suitable source of current supply, such as the igni- 40 tion or lighting circuits of an automobile, or a separate battery or generator circuit as may be feasible or necessary.

With the foregoing and other objects in view, the invention resides in the certain novel and useful construction and arrangement of parts as will be hereinafter more 45 fully described, set forth in the appended claims, and illustrated in the accompanying drawings, in which:—

Figure 1 is a fragmentary detail, partly in section, of an engine manifold showing the preferred embodiment and application of the invention thereto, and,

Fig. 2 is an enlarged longitudinal section through the device per se.

Referring to the drawing, the numeral 10 55 indicates a conventional form of engine manifold, 11 the point of connection there-

with of a carburetor (not shown), and 12 an 60 interiorly threaded opening in the inlet portion of the manifold adapted for the insertion and securing therein of a heating at- tachment forming the subject matter of the present invention.

The heating attachment comprises an elongated cylindrical shell 13 closed at its inner 65 end and having the outer end portion of its wall thickened to a greater diameter to provide an exteriorly threaded portion 14 adapted for engagement in the boss 12 of the engine manifold 10, the inner portion of the shell 13 being of a length to extend entirely 70 across the passage leading to the manifold proper from the end of the same to be connected to a carburetor. The extreme outer end of the portion 14 beyond the threaded section thereof, is formed to provide a headed 75 portion 15 having flat tool or wrench engaging surfaces for facilitating the insertion and removal of the shell to and from position within the boss 12.

Extending within the bore of the shell 13, 80 and spaced concentrically of the wall there- of, is a core 16 of an insulating material of high heat resisting quality, the inner end of which is supported in position by means of a screw 17 threaded through the integral 85 end wall of the shell 13, while the outer end of the same is formed with a cylindrical en- largement 18 which snugly fits the bore of the shell inward from its open end. The outer thickened end portion of the shell 13 90 is formed with a counter-bore 19, concen- trically of the main bore thereof, and snugly fitting into this counter-bore is a plug 20, also of an insulating material, and through the longitudinal center of which is extended 95 a binding post or screw 21, the free threaded end of the latter being provided with a bind- ing nut 22, for the connection thereto of one conductor 23 of the current supply cir- 100 circuit (not shown). The inner headed end of the binding post or screw 21 is disposed within a semi-circular recess 24 formed in the inner end of the plug 20, and which provides for a space between the same and the opposed end of the core 16. Coiled 105 around the core 16 is a heating element or resistance wire 25 which has one end secured beneath the inner headed end of the bind- ing post or screw 21, and its other end en- gaged in the socket opening 26 formed in 110 the inner end of the core 16 for the reception of the supporting screw 17, which screw 17,

together with the shell 13 forms a ground connection between the coil 25 and the engine manifold. For retaining the plug 20 securely in position within the counter-bore 19 of the shell 13, a set screw 27 is threaded radially inward of the thickened end portion 15, so that its inner end frictionally contacts the periphery of the plug.

From the foregoing, it will be obvious that all of the fuel drawn from its source of carburation will be subjected to the heating effect of the coil within the shell 13, in addition to being further conditioned for more perfect combustion by its impacting action against the wall of the latter, since the shell extends entirely across the path of the fuel in a manner to provide restricted passages at its opposite sides for the flow of the fuel around the same to the manifold proper.

For the installation of these heating coils, which may be manufactured as separate units capable of general application to explosive engines, it is contemplated to simply drill a suitable sized opening in the manifold as now provided on engines, thread the same for the reception of the threaded portion of the shell 13, and close the opening with a suitable screw-plug (not shown), when the heating device is not in use, as in extremely hot weather. In cold weather, or when otherwise desired, this plug can be removed, and the shell 13 threaded into position, with the binding post of screw thereof properly connected to one side of the current supply circuit as hereinbefore stated.

It is to be thoroughly understood that, while the attachment has been described in specific terms and illustrated in preferred details of construction, arrangement and application, various changes and modifications of the same may be provided or re-

sorted to without departing from the spirit and scope of the invention.

Having thus fully described the invention, what is claimed, is:

1. An attachment of the class described comprising a cylindrical metal shell closed at its inner end, and adapted to be removably inserted into the manifold of an engine, a core of insulating material disposed within said shell and spaced concentrically of the bore thereof, a coil of resistance wire wound on said core, a screw threaded inwardly of the closed end of said shell and engaging the inner end of said core to space the same concentrically thereof, said screw acting to secure the inner terminal of said coil and to ground the same to said shell, and an insulated binding post carried at the outer end of said shell and having connection with the other terminal of said coil. 50

2. The combination with an explosive engine including the carbureter connections leading to and connecting the intake manifold of the engine, of a hollow metal shell closed at its inner end and adapted for threaded engagement with an opening formed in the intake manifold of the engine and extending in the path of the fuel flowing therethrough from the carbureter connections thereof, a core of insulating material extending within said shell and spaced from the walls thereof, a closure plug for the outer open end of said shell, a binding 70 post carried by said plug closure, an electrically heated coil wound on said core and having one of its ends connected to said binding post and the other end thereof grounded to said shell and intake manifold. 80

In testimony whereof, we affix our signatures hereto.

JOHN T. ELLIS.
ORA A. KERN.
